UNITED STATES PATENT OFFICE

ROBERT F. DARBY, OF CHICAGO, ILLINOIS, ASSIGNOR TO AMERICAN STEEL FOUNDRIES,
OF CHICAGO, ILLINOIS, A CORPORATION OF NEW JERSEY

SHAKER ARM

Application filed February 11, 1929. Serial No. 338,981.

This invention pertains to grate assemblies, and more particularly to shaker arms associated with said assemblies.

In grate assemblies, particularly those of the table type, it is very important to provide a shaker arm which will satisfactorily perform its work. As will be appreciated, the whole grate assembly is subjected to hard usage with the result sometimes that parts are broken and must be replaced. Heretofore difficulties have been encountered in selecting an entirely satisfactory shaker arm which must be inexpensive and capable of being conveniently located in such a manner as will not affect the strength of the parts of the assembly nor the draft of the assembly in operation.

It is therefore an object of this invention to provide a shaker arm separable from the grate assembly, one which is sturdy, readily applied and one which fulfills all requirements of service and manufacture.

Another object is to provide a shaker arm so constructed as to be readily applied to existing grate assemblies as well as to specially designed assemblies.

A further object is to provide a shaker arm for grate assemblies which may be applied to the assemblies at convenient points along the length thereof.

Still further object is to provide a shaker arm which while adapted for a plurality of fastening means is yet arranged to be fastened as a right or left through the same fastening means.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a fragmentary side elevation of a grate bar support, showing the application of a shaker arm thereto;

Figure 2 is a sectional top plan view of the assembly illustrated in Figure 1, the same being taken substantially in the plane as indicated by the line 2—2 of Figure 1;

Figure 3 is a sectional end elevation through the grate supporting frame, the same being taken substantially in the plane as indicated by the line 3—3 of Figure 2;

Figure 4 is a fragmentary side elevation of a different form of grate bar support, showing the application of a modified form of shaker arm thereto;

Figure 5 is a sectional top plan view of the modified form of shaker arm, the same being taken substantially in the plane as indicated by the line 5—5 of Figure 4; and

Figure 6 is a sectional end elevation through the modified form of grate supporting frame, the same being taken substantially in the plane as indicated by the line 6—6 of Figure 5.

Referring first of all to the form of shaker arm illustrated in Figures 1 to 3 inclusive, which shaker arm is adapted for use with a supporting frame of a grate bar structure wherein a single longitudinal rib is utilized, this single rib 10 of the support is shown with the oppositely extending transverse securing lugs 12, said rib 10 being provided with longitudinal spaced apertures 14. The shaker arm is provided with a shank 16, shown of substantially arcuate shape, the end thereof being provided with an aperture 18 for the reception of actuating means, such as a link, and said shank terminates in a bifurcated head portion 20 provided with upwardly extending jaws 22, each of said jaws extending in opposite directions, being provided with sloping portions 24, the plane of which intersects at the top 26 of the head, being so formed for foundry purposes. Each of said jaws is provided with an aperture 28.

adapted to register with the respective apertures 14 and to receive securing means, such as the rivets 28, securely fastening said shaker arm to the frame, it being understood that 5 a base portion 30 of the bifurcated head may contact the bottom of the rib 10, providing a tighter fit.

With this construction, wherein a plan of the jaws is substantially Z-shaped, it will be 10 seen that the shaker arm may be assembled for any position, that is, as either a right or left as desired, in spite of the fact that a plurality of fastening means is used, one of said fastening means being used for each jaw.

15 Referring now to the modification illustrated in Figures 4 to 6, it will be seen that the supporting frame 50 of the grate bar assembly comprises spaced longitudinally extending members 52 and 54, the members 52 20 and 54 being provided with apertures 56 and 58 disposed on the same level but in staggered relation to each other. The shaker arm 60 is of any desired shape, such as arcuate, the shank 62 being provided with an aperture 25 64 for the attachment of an actuating means, such as a link, the opposite end of said shank terminating in a head portion 66 provided with spaced oppositely extending lugs 68 and 70. The head of the shaker arm is substantially Z-shaped in plan, as shown in Figure 5, and each of the lugs is provided with apertures 72 and 74 respectively adapted to register with apertures 56 and 58 whereby 30 securing means, such as rivets 76, may be inserted into the registered apertures for securing the shaker arm in operative position with respect to the grate assembly. As before, the disposition of the lugs 68 and 70 makes it possible for the shaker arm to be assembled 35 40 with the grate bar as a right or a left as desired, though a plurality of fastening means between the shaker arm and grate are used, thus forming a very advantageous structure.

With the construction shown, it will be appreciated that a very compact and serviceable form of shaker bar and assembly is provided, and it is to be understood that I do not wish to be limited by the exact embodiment of the device shown, which is merely by way of 45 50 illustration and not limitation, as various and other forms of the device will of course be apparent to those skilled in the art without departing from the spirit of the invention or the scope of the claims.

55 I claim—

1. In a grate bar assembly, the combination of a support having spaced apertures disposed therein, a shaker arm for moving said support, said arm having spaced jaws 60 for embracing engagement with said support, each of said jaws being provided with an aperture adapted to register with one of said first named apertures, and securing means disposed through registered apertures. 65 70 75 80 85 90 95 100 105 110 115 120 125 130

tion of a support having spaced apertures disposed therein, a shaker arm for moving said support, said arm having members disposed thereon forming a substantial Z-shaped member in plan view, said members being provided with apertures adapted to register with said first named apertures, and securing means disposed through the registered apertures.

Signed at Chicago, Illinois, this 26th day 75 of January, 1929.

ROBERT F. DARBY.
